RAIL CONNECTION.

1,056,658.

Specification of Letters Patent.

Patented Mar. 18, 1913.

Application filed August 15, 1912. Serial No. 715,154.

To all whom it may concern:

Be it known that I, GEORGE FUSSELL, citizen of the United States of America, residing at Vancouver, in the Province of 5 British Columbia, Canada, have invented a new and useful Rail Connection, of which the following is a specification.

This invention relates to a railway joint connection which has been particularly designed as a substitute for the bolt-connected fish plates which are in common use. These bolt connected fish plates may form a satisfactory rail joint when bolts of sufficient strength are used and when these bolts are maintained tightly screwed up but under the intense vibration to which they are exposed by passing traffic it is difficult to maintain this condition and they rapidly become slack and the joint is not then an effective one as 10 it is too yielding and permits one rail end to move down in relation to the other as a wheel passes over the joint, with obvious injury to both track and rolling stock. These objections are overcome in the invention which is the subject of this application, 15 by the provision of an integral joint connection comprising two plate members extending along both sides of each rail from the joint, which plate members are strongly 20 tied together to exert the required hold upon the rails by an integral connection extending between them, provision for which is formed in the web of each rail at their abutting joint.

This joint connection is so proportioned 25 that the rail ends are required to be forced into it and these ends closely fit, while the ends of the connected joint plates exert a powerful resilient hold on each rail adjacent to its end. In other words the plates are curved and arranged with the ends nearer together than the middle portion so that they must be forced apart, as the rail ends are inserted as best indicated in Fig. 2 of 30 the drawing.

The general construction and essential features of this joint connection are particularly described in the following specification, reference being made to the drawings by 35 which it is accompanied, in which:

Figure 1 is a side elevation of the joint as applied. Fig. 2, a plan of the joint connection apart from the rail. Fig. 3, an elevation of the rail joint with the near plate removed showing the relation of the rail ends to the connection. Fig. 4, a cross section of the joint on the line A in Fig. 1, and Fig. 5, a cross section of the joint on the line B.

In these drawings 2 represents the ends 60 of the rails which it is required to connect. From the end of each rail a triangular portion 4 is removed from the web between the head of the rail and flange forming the diagonal half of a square, which square is complete when the rail ends abut against one another.

The rail connection comprises two plate members 5 extending along each rail a sufficient distance to afford the necessary support against flexure at the joint. Each plate member 5 will preferably bear, as is usual with a fish plate, against the underside of the head of the rail and a corresponding amount of the upper side of the flange, as 70 shown at 6, in the cross sections, and may have a short bearing on the web and its fillet, as at 7. Between the bearing rib-like portions of the plate members 5 where they engage the web as at 7, the plates are preferably spaced from the web, as best shown in Fig. 5 of the drawing, to be out of contact with the web between the upper and lower "points" 7, shown best in Fig. 5 of the drawing. These plate members 5 are connected together at their midlength by a portion 8, which is integral with the plates and is shaped as shown in Fig. 3, to conform to the square formed by the two triangular portions removed from the webs of the rails. 80 Adjacent to the middle, the distance between the contact bearings 6 of each plate is such that the rail ends will closely fit between them and this width between the bearings 6 is initially less at the ends of the 90 plates, see Fig. 2, so that the rail ends require to be forcibly driven or pressed into their bearings in the joint connection. To facilitate this entrance of the rail ends the plates may have a slight entering flare or 95 120

taper, as shown in Fig. 2. The lateral depth of the connection at the middle, where the two plates 5 are joined together by 8, must be sufficient to afford ample strength 5 to the plate members and enable them to exert the necessary powerful grip at their ends on the rails, and the plate members will be strongly webbed up from the ends to the middle in the furtherance of this object. To 10 lighten the connection and avoid the effects of unequal shrinkage, the connecting member 8 may be cored through from one side to the other.

In applying this connection, the rail ends 15 will be forcibly inserted between the plates 5, and will be pressed tightly up against the connecting member 8 leaving only sufficient room for expansion according to the temperature at which the track is laid. Being 20 thus forcibly pressed in the rail ends will closely fit between the seats 6 of the plates at the middle and at the ends, that at the middle being a rigid hold while that at the ends will be strongly resilient, the resilience 25 being such that it will not yield under traffic but will maintain a constant strong grip to compensate for any slight wear.

The construction (best shown in Fig. 2), whereby the ends of the plates are brought 30 closer together than the plates are in the middle is of importance so as to insure that the greatest holding pressure is exerted at the extreme ends of the plates where the greatest supporting strength should be applied. This forms an essential feature in 35 the invention as otherwise a satisfactory fit would be difficult to attain.

With the end rails of a section, the length 40 of which may vary according to the requirements of construction and repair, the connecting plate members 5 cannot be formed integral as the rail ends cannot be introduced; but the same general idea is preserved by securely fastening the two plates 45 5 together by a heavy rivet through the cored aperture of the connecting portion 8 or by other approved means. It is also believed that if a satisfactory rail connection is introduced much of the trouble in maintaining 50 railway tracks will be avoided and once laid the track will be permanent within the life of the rail so that necessity may not exist for removing isolated rails.

I am aware that rail connections have 55 previously been used wherein a triangular portion has been removed from the ends of the rail for the introduction of a member to support the rail ends against vertical movement in relation to one another and that rail 60 end supports have been used having extensions of each side of the rail which are integral with one another. This last has, however, included a portion of the tread of the rail and does not conflict with the construc-

tion here set forth as essential features of 65 this invention. These essential features are set forth in the following claims.

Claims:

1. A rail connection, comprising two plate members, one on each side of the rail, which plate members are provided throughout their length with contact seats to bear against the underside of the head and the corresponding upper side of the flange of the rail, said plate members being slightly 75 concave toward one another and connected together at their midlength by a portion which will secure them apart at their midlength a distance equal to the distance apart of the contact seats on the rail, said concavity serving to bring the ends of the plates closer together than the middle portion of the same.

2. A rail connection, comprising two plate members provided throughout their length with contact seats to bear against the underside of the head and the corresponding upper side of the flange of the rail and also against a portion of the web adjacent thereto, said plate members being slightly 80 concave on the side toward the rail and strongly connected together at their midlength at a distance apart corresponding to the distance apart of their seats on the rail, said connecting portion being integral with 85 the plates, said concavity serving to bring the ends of the plates closer together than the middle portions of the same.

3. A rail connection, comprising two plate members connected together at their 100 midlength by a portion integral with the plate, said connecting portion being square in cross section, the diagonal of the square vertically disposed, said plate members having contact seats throughout their length to 105 bear on the underside of the head and corresponding upper side of the flange on each side, the distance between the contact seats of the plates at each end being less than the distance between the contact seats of the rail 110 when free from the rails.

4. A rail connection, comprising the combination with rail ends from the webs of which a triangular portion has been removed, of plates fitting closely between the 115 rail head and flange end on the web, said plates connected together by a portion integral with the plates passing through the space formed between the rail ends, the ends of said plates having a strong resilient grip 120 on the rail.

5. A rail connection, comprising the combination with rail ends from the webs of which portions have been removed offering communication between the two sides of the 125 rail, of plates fitting closely between the rail head and the flange on each side of the rails and against the web on each side, said plates

connected together through the rails by a portion integral with the plates and conforming to the aperture in the rail joint, said plates being closer together at the ends than at the middle when free of the rails and having at the ends an entering flare to enable the rail ends to be inserted.

In testimony whereof I have signed my name to this specification in the presence of two subscribing witnesses.

GEORGE FUSSELL.
